[57] CLAIM

The ornamental design for a wrist purse, substantially as shown and described.

DESCRIPTION

FIG. 1 is a front elevational view of a wrist purse showing our new design;

FIG. 2 is a rear elevational view thereof;

FIG. 3 is a top plan view thereof;

FIG. 4 is a bottom plan view thereof;

FIG. 5 is a left end elevational view thereof;

FIG. 6 is a right end elevational view thereof; and

FIG. 7 is a perspective view showing the manner in which the purse is worn on the wrist.

The partial showing of shading indicating a fabric texture on FIGS. 1 and 7 is understood to be continuous on the surfaces where shown.

FIG. 1.**FIG. 2.****FIG. 3.****FIG. 4.****FIG. 5.****FIG. 6.****FIG. 7.**
